UNITED STATES PATENT OFFICE

BENJAMIN M. HAMLIN, OF RACINE, WISCONSIN, ASSIGNOR TO WHEARY TRUNK COMPANY, OF RACINE, WISCONSIN, A CORPORATION OF WISCONSIN

LUGGAGE CARRIER

Application filed November 15, 1928. Serial No. 319,578.

One objection to hand luggage of the Gladstone bag type is the impossibility of carrying a garment, such as a man's coat or complete suit, without wrinkling and while attempts have been made to overcome this by the construction of miniature wardrobe trunks having a garment section with hangers, their necessarily increased weight and size does not permit their being conveniently carried. Therefore, this invention contemplates as an object the provision of an improved luggage carrier the overall weight and size of which is no greater than that of the conventional Gladstone bag or the like and which has provision for carrying a garment without creasing or wrinkling the same.

Another object of this invention resides in the provision of an improved form or hanger about which a man's suit or other garment may be draped to retain the same against wrinkling or creasing while packed in a suit case or other type of luggage carrier.

A further object of this invention resides in the provision of an improved luggage carrier in which either the cover or the main section has a compartment therein for receiving a form or hanger about which a complete suit may be draped in a manner to prevent wrinkling or creasing thereof irrespective of how long it is retained in the case, the compartment having cushioning means cooperating with the form or hanger to hold the garment in shape.

A still further object of this invention resides in the provision of an improved luggage carrier having a form or hanger removably mounted therein whereby a garment may be secured against wrinkling and the form used apart from the carrier as a hanger.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have il-

lustrated two complete examples of the physical embodiment of my invention constructed according to the best modes I have so far devised for the practical application of the principles thereof, and in which:

Figure 1 is a perspective view of a luggage carrier of the case type embodying my invention, the case being in open position;

Figure 2 is an elevational view of the improved garment carrying form or hanger illustrated apart from the case and having a pair of trousers draped thereabout prior to the placing of a coat thereon.

Figure 3 is a fragmentary view, partly in section and partly in elevation, of one corner portion of the case cover and illustrating the manner of detachably securing the garment form or hanger therein;

Figure 4 is a fragmentary view, partly in section and partly in elevation, taken through the garment compartment or cover of the case on the plane of the line 4-4 of Figure 1, and

Figure 5 is an elevational view similar to Figure 2 and illustrating a slightly modified hanger.

Referring now more particularly to the accompanying drawings in which like numerals designate like parts throughout the several views, 5 represents the main section of a case having a cover or lid 6 suitably hinged thereto along one marginal edge. The case is further provided with conventional locking devices 7 and a handle 8.

The main section of the case may be provided with a series of partitions 9 dividing it into compartments 10 for various articles such as skirts, ties, collars and the like and the cover 6 preferably is of a depth sufficient to receive one or more garments depending upon the desired capacity of the carrier. A closure 11 is hinged to the cover along its lower edge to define a garment compartment 12 and suitable snap fasteners or the like 13 are provided for securing the closure in its closed position with its marginal edges abutting shoulders or stops 14 formed in the cover.

The case illustrated in the drawings is particularly designed for receiving men's

clothes and its garment compartment has capacity for one suit which is draped or secured about an improved garment form or hanger 15 which, in addition to having means for hanging the garment, prevents the wrinkling or mussing thereof while in the case. The form or hanger 15 consists of a skeletonized frame, the upper section of which forms a garment hanger 16 of substantially conventional design with shoulder engaging portions 17 and a horizontal portion 18 over which a pair of trousers may be hung.

In placing a man's suit on the form or hanger, the trousers are passed through the opening 19 above the horizontal portion 18 whose inner edge over which they are draped at about a medial point, is preferably provided with a cushioned substantially round edge 18' to reduce the sharpness of the fold, to hang along one side of the form below the hanger 16. The coat and vest are next placed on the hanger 16 with the shoulders engaging the portions 17 in the usual manner, with the trousers therein as in a conventional type of hanger. With the coat closed and the sleeves arranged in proper position the form is turned to fold the suit over its top edge 20 which is provided with a cushioned roll 21 to prevent creasing, after which the suit may be rearranged to insure the garment being folded along its normal creases.

The frame is then secured in the compartment 12 with its edge 20 uppermost in the manner illustrated in Figure 1, being removably supported therein by lateral projections 22 secured to the upper corners of the frame, as at 23, and engaging rails or supports 24 secured along the side walls 25 of the cover 26 slightly spaced from the top wall 26.

The depth of the compartment 12 within the cover, in the event the case is designed to carry but one complete suit is just sufficient to receive a single suit and the rear wall 27 of the cover and the closure 11 have their inner surfaces preferably padded or cushioned, as at 28, to maintain a yielding pressure on the garment which prevents its shifting and further protects the same against wrinkling. As will be apparent the top portion of the coat which is shown outermost in Figure 1 is held in position by the tension applied by the lower portion being folded over the form and the lower portion of the garment which is innermost with reference to Figure 1 is held in position on the form by an elastic or belt member 29 which has a buckle or other fastening 30 to permit its being secured about the garment as will be readily apparent.

The form 15 may be provided with a folding hook or the like 31 adjacent its edge which is lowermost when secured in the cover 6 so that it may be removed from the carrier and utilized as an ordinary garment hanger.

In Figure 5, a slightly modified construc-

tion of form is illustrated in which the hanger 16 is not an integral part thereof, but is separate therefrom and has a substantially U shaped hook or fastening 32 to engage over the form lower edge as illustrated and a folding hook 33 so that the hanger proper may be used apart from the form, as will be readily apparent. For this form of my invention, the manner of draping the garment thereon is identical with that described in connection with the disclosure in Figures 1 to 4, inclusive and, therefore, further description is deemed unnecessary.

From the foregoing description taken in connection with the accompanying drawings, it will be readily apparent to those skilled in the art to which an invention of the character described appertains that I provide an improved and novel luggage carrier of the case type having provision for conveniently carrying a complete suit or other garment without its being creased or wrinkled and one which does not increase the weight or size of the carrier.

I claim:

1. In a luggage carrier, a garment form of a length less than the length of a garment, means whereby a garment may be hung from the form, the garment being foldable over the edge of the form remote from said means, cushion means along the edge of the form over which the garment is folded to protect the same against wrinkling, and means carried by the form and engaging the free end of the garment to secure the same against the adjacent side of the form.

2. In a baggage carrier including a main section member and a cover member, one of said members having a garment compartment therein, an internal cover for said garment compartment, a form about which a garment is adapted to be draped to be held in position against wrinkling, means for mounting the form with the garment thereon in the compartment, and cushion means carried by said internal cover and one of said members engageable with opposite sides of the garment in the compartment to prevent shifting thereof.

3. In a baggage carrier of the character described having a pair of hinged sections, one of said sections having a garment compartment, a garment receiving form upon which garments may be draped and folded over, means carried by the garment receiving form for preventing creasing of the garments at its folds, means readily removably mounting the garment receiving form in said compartment, a cover movable to engagement with garments in the compartment, and cushion means carried by one compartment wall and the cover for preventing wrinkling of the garments.

4. The combination with a baggage carrier of the case type, of a garment carrying

- frame of a length less than that of the garment to be placed thereon, a coat receiving portion at one end of the frame, a trouser receiving part, means carried by the trouser receiving part for preventing creasing, cushion means carried by the frame at its end opposite the coat receiving portion, a coat and trousers being foldable over said cushion means, and supporting members carried by the frame whereby the frame may be mounted with its cushion means uppermost.
5. In a hand luggage case, including a main section and a cover hingedly connected therewith, means for supporting garments within the case to lie over the main section and extend into the cover comprising, a frame having sides and a transverse end member over which the garments are folded, and garment carrying means between the sides of the frame and on which the garments are positioned preparatory to being folded over the end member.
6. In a hand luggage case including a main section and a cover hingedly connected therewith, means for supporting a man's suit within the case to lie over the main section and extend into the cover comprising, a frame having sides and a transverse end member over which the suit is folded, a transverse trouser receiving bar between the frame sides and adjacent their ends opposite the transverse end member but substantially parallel with said transverse end member, and means adjacent the transverse trouser receiving bar adapted to have the shoulder portions of the suit engaged therewith.
7. In a hand luggage case including a main section and a cover hingedly connected therewith, means for supporting a man's suit within the case to lie over the main section and extend into the cover comprising, a frame having sides and a transverse end member over which the suit is folded, said frame being movably mounted in the case with its transverse end member remote from the hinged connection of the main section and cover, and garment hanger means between the sides of the frame but spaced from the transverse end member and including, a transverse trouser receiving bar substantially parallel with the transverse end member, and a part adapted to have the shoulder portions of the suit engaged therewith, the suit being positioned on the garment hanger means preparatory to being folded over the transverse end member.
8. In a hand luggage case including hingedly connected complementary sections, means for supporting garments within the case to overlie one section and extend into the other, comprising garment hanger means having a part adapted to have the shoulder portions of a garment engaged therewith and a trouser receiving bar inwardly of the shoulder part, a transverse rigid garment support

spaced from the hanger means and substantially parallel with the trouser receiving bar, and means connecting the hanger means and the garment support, said last mentioned means being of less length than the garments to be carried so that garments draped over the hanger means may be folded over the transverse garment support.

9. In a hand luggage case including hingedly connected complementary sections, a one-piece garment form for supporting garments within the case, said form having a part adapted to have the shoulder portions of a garment engaged therewith, a trouser receiving bar inwardly of the shoulder part and a rigid transverse garment supporting bar spaced from said part a distance less than the length of a garment to be carried so that garments draped over said part and trouser receiving bar are foldable over the transverse bar, and means for mounting the form in the case with said shoulder engaging part adjacent the hinged connection of the complementary sections.

10. In a hand luggage case including hingedly connected sections, means for supporting garments within the case to overlie one section and extend into the other comprising a frame having sides and a transverse end member over which garments are foldable to lie on both sides of the frame, means adjacent the end of the frame opposite said transverse end member on which garments are draped preparatory to being folded over the transverse end member, and means for mounting the frame in the case with the transverse end member adjacent the ends of the complementary sections opposite their hinged connection when the case is closed.

In testimony whereof I have hereunto affixed my signature.

BENJAMIN M. HAMLIN.
